UNITED STATES PATENT OFFICE.

MORRIS B. BREWSTER, OF COLUMBUS, OHIO.

AUTOMATIC STOKER.

No. 880,622.

Specification of Letters Patent.

Patented March 3, 1908.

Application filed January 25, 1907. Serial No. 363,938.

To all whom it may concern:

Be it known that I, MORRIS B. BREWSTER, a citizen of the United States, residing at Columbus, in the county of Franklin and 5 State of Ohio, have invented certain new and useful Improvements in Automatic Stokers, of which the following is a specification.

My invention relates to new and useful improvements in automatic stokers.

10 The object of the invention is to provide an over head fed stoker which while comprising means for controlling the delivery of the coal, obviates the necessity of expensive and complicated machinery or valves of the 15 shearing type.

A further feature resides in a universal connection in the feeding mechanism which permits the parts to be positively connected irrespective of the relative positions of the 20 locomotive and tender.

Among other provisions are self closing valves, a common operating shaft and a particular form of distributing table.

Finally the object of the invention is to 25 provide a device of the character described that will be strong, durable, efficient and simple and inexpensive to manufacture. Also one in which the several parts will not be liable to get out of working order.

30 With the above and other objects in view, the invention consists of the novel details of construction and operation, a preferable embodiment of which is described in the specification and illustrated in the accompanying 35 drawings, wherein:

Figure 1 is a front elevation of my stoker and a portion of the rear end of a locomotive boiler, Fig. 2 is a longitudinal sectional view taken on the line $x-x$ of Fig. 1, Fig. 3 is a 40 plan view of the distributing table and the nozzles, Fig. 4 is a plan view of the socket casting and the piston valve, and Fig. 5 is a vertical sectional view of the piston valve.

In the drawings the numeral 1, designates 45 the combustion chamber of a locomotive and 2, the rear boiler sheets, 3, the ordinary fire-door frame and 4, the combustion chamber opening, while at 5 a portion of the cab roof is shown.

50 Above the fire-door frame 3, a casting 6 is bolted to the boiler sheets. This casting comprises a forwardly extending web 7 which terminates in a socket or bowl 8 open at its bottom and having downwardly extending front and rear plates 9. Between these 55 plates hollow valves 10 of the V-shape type

are mounted to swing to each side on rods 11 passing through the plates. It is to be understood that coal passes through the bowl 8, the valves acting as cut-off so that 60 the passage of the coal may be regulated and controlled. The valves are so hung and weighted as to swing into contact beneath the center of the bowl, thus being self closing. Suitable means may be arranged to limit this 65 swinging movement.

The plates terminate a short distance below the valves and register, but do not contact, with an elbow hopper 12 forming part of a fire-door 14 and having communication 70 with the combustion chamber through the frame 3 and the opening 4. The fire-door is shaped and proportioned so as to be substituted for the usual fire-door without altering any of the standard parts and thus may be 75 swung open to permit "firing" in the usual way.

As in my stoker and conveyer patented November 7, 1905, Number 803,805 I propose to convey the coal overhead from the 80 tender to the feeding means, employing a pipe casing 15 and a spiral conveyer 16 mounted in the casing, the said casing being suitably supported from the tender. In my previous and similar stokers it has been customary to use a wide mouth hopper on account of the lateral swinging of the conveyer casing when the locomotive and tender are taking curves and the swaying due to fast running. Even with the wide mouth hop- 90 per, which consumes considerable room in the cab, the coal is often thrown past the sides of the hopper and to overcome this objectionable feature I have devised the following construction. 95

Within the bowl 8 an open ended ball 17 is mounted to freely turn so that a ball and socket joint is provided. At its upper end the ball is formed with a collar 18, which snugly receives an upwardly extending pipe 19, the latter loosely receiving a spout 20, which telescopes into the pipe. A hook 21 secured to the spout engages a link 22 fitting about the bearing 16^a of the conveyer 16 as shown in Fig. 1. It is evident that as the 100 conveyer casing swings, the spout and pipe also swing, the hook and link effecting a positive connection, so that the conveying of the coal is continuous and the liability of lumps of coal being thrown about the cab 105 obviated.

As will be observed the coal passes from the

conveyer through the spout 20, pipe 19, ball and socket joint, valves 10 and hopper 12 to the fire opening 4. Within the combustion chamber 1 and at the bottom of the fire opening, a distributing table or shelf 23 is secured to the inner sheet 2 by a downwardly inclined flange 24. The table is formed on its upper surface with an inwardly extending and flaring central distributing ridge 25. This ridge also inclines upwardly toward the combustion chamber. On each side of the ridge a plurality of nozzles 26 and 27 and pipes 28 are arranged, preferably three on a side. The pipes are connected with means for supplying a fluid under pressure which is emitted from the nozzles intermittently. The nozzles 26 are curved and extend horizontally over the table 23, the outermost nozzles being directed toward the sides of the combustion chamber, while the inner nozzles 26 are directed diagonally toward the forward corners of the said chamber. The nozzles 27 terminate in the fire opening 4, in line, so that the fluid is ejected against the sides of the ridge 25. The coal passing through the opening 4 is delivered onto the table 23 about and over the nozzles; thus when the fluid is emitted from the nozzles, it distributes or discharges the coal from the table to the different parts of the combustion chamber toward which the nozzles are directed. The fluid from the nozzles 27 forces the coal against the ridge 25, which owing to its forwardly inclined and flaring nature, scatters the coal well forward, but prevents any quantity banking in one place, an even distribution thus being obtained. Suitable provision for adjusting the nozzles may be made.

40 The means for supplying and controlling the supply of fluid to the pipes comprises a manifold 29 connected with the pipes 28, in which latter valves 30 are arranged over the said manifold. The amount of fluid passing through each pipe may thus be controlled. The manifold has connection through a pipe 31, with a valve cylinder 32 mounted on the web 7 of the casting 6. Fluid under pressure is supplied to the cylinder by a pipe 33. The pipes 31 and 33 communicate with the cylinder through ports 34 and 35 respectively, so that the fluid may pass into the cylinder through the port 35 and out through the port 34, the ports being in close proximity. A piston valve having separated heads 36 and 37 is mounted to move vertically in the cylinder and provided with an upwardly extending piston rod 38. This rod has pivotal connection with an offset rod 39, the latter having rigid connection with the ring 40 of an eccentric 41 mounted on a shaft 42 supported in bearings 43 secured to the roof 5 of the locomotive cab. By means of this construction the heads are reciprocated in the cylinder, so that when the eccentric 41 is at

the greatest or lowest point of its throw, the valve will be at its lowest point, the head 36 standing just below the port 34 and the head 37 just above the port 35, permitting the fluid to flow from the pipe 33 through the ports to the pipe 31 and from there to the nozzles as described. As the valve is raised by the eccentric, the head 36 gradually closes the port 34, the supply of fluid to the nozzles being thus cut off. The throw of the eccentric is limited so as not to carry the head 36 over the port 35 on the upward stroke.

It is evident that some means for opening the valves 10 must be provided and for this purpose I mount on the shaft 42 a second eccentric 45 having a ring 46. This eccentric is set opposite to the eccentric 41 with relation to the revolution of the shaft. A cross-bar 47 is carried by the ring and extends transversely of the shaft. Chains 48 are suitably secured on the ends of the cross-bar and at their lower ends have connection with ears 49 formed on the outer ends of the valves 10. When the eccentric is at the lowest point of its throw, the valves are closed as shown in Fig. 1. The valves are opened or swung outward by the chains as the eccentric 45 is moved upward, permitting the coal to pass between the plates 9 to the hopper 12. As before stated the valves are weighted and so hung as to be self closing, so that after the eccentric swings over its center, the cross-bar is lowered and the valves permitted to swing together again interrupting the passage of the coal.

It will be observed that by arranging the eccentrics opposite or at halves, the valves 10 are opened and coal allowed to pass to and accumulate in the fire-opening 4 and upon the table 23, so that the valves are closed when the head 36 uncovers the port 34 and permits the fluid to pass to the nozzles and distribute the charge of fuel in the combustion chamber. It will further be noted that no valve closing gearing or cylinders or other complicated mechanism is mounted about the fire-door or on the boiler sheets and also access may be had to any of the parts.

The shaft 42 has connection through a universal coupling 50 with a power shaft 51 driven from and carried by the tender. By provision of the coupling, the shaft may be readily disconnected when the locomotive and tender are uncoupled. The coupling also takes care of the independent motion of the locomotive and tender incidental to taking curves and uneven track etc. It is obvious that by regulating the speed of the shafts, the feeding and distribution of the fuel may be controlled.

What I claim, is:

1. In an automatic stoker, the combination with a combustion chamber, of means for feeding fuel to the combustion chamber

comprising a hopper, a fixed conveying member arranged above the hopper, a movable part having connection with said conveying member, and a receiving part having 5 movable connection with the movable part.

2. In an automatic stoker, the combination with a combustion chamber, of a hopper for feeding fuel to the chamber, a fixed fuel conveying member arranged above the hopper, means for controlling the passage of the 10 fuel through the fixed member, means for conducting fuel to said member having movable connection therewith, and means for conveying fuel to said conducting means.

15 3. In an automatic stoker, the combination with a combustion chamber, of a regulated fuel introducing means therefor comprising a fixed fuel receiver carried by said combustion chamber, an intermittently operated valve arranged therein, a conveyer, and a two part extensible section arranged between said conveyer and said fixed receiver, one of said parts having a universally 20 movable connection with said receiver, substantially as described.

25 4. In an automatic stoker, the combina-

tion with a combustion chamber of a regulating fuel introducing means therefor comprising a fixed fuel receiver carried by said combustion chamber having a regulating 30 valve therein, a conveyer, and a two part telescopingly extensible section arranged between said conveyor and said fuel receiver, having movable connection with said conveyer and said receiver, substantially as de- 35 scribed.

5. In an automatic stoker, the combination with a combustion chamber, means for feeding fuel to said chamber comprising a stationary receiver and a fixed conveying 40 member above said receiver having a regulating valve therein, and means for conveying fuel to said feeding means having universal connection therewith, substantially as described. 45

In testimony whereof I affix my signature in presence of two witnesses.
